APPARATUS FOR REMOVING DUST
FROM GASES

Ernest Mercier and Marcel Ehlinger, Paris, France, assignors, by mesne assignments, to Moore, Inc., Atlanta, Ga., a corporation of Georgia

Application March 29, 1949, Serial No. 84,144
In France April 3, 1948

15 Claims. (Cl. 183—79)

1

The present invention has for its object apparatus for removing dust from gases which consists in leading the gas into the apparatus at high speed as a thin layer (about 1 cm. in thickness or even less) and leading it out as a thin layer of substantially the same thickness after a change of direction of about 180°, or at least a very substantial and abrupt change of direction, has been imposed upon the flow of the gas, the mean radius of curvature of the bend being quite small i. e. likewise of the order of one centimetre or even less, whereby considerable momentums are set up which tend to hurl the dust particles conveyed towards the outside of the bend whereby the desired dust removal is secured.

The invention is also concerned with apparatus by means of which gases resulting from the combustion of coal can be purified by removing therefrom the ash and clinker therein, which apparatus is capable notably of dealing with gases at high temperatures and with gases under pressure.

Apparatus of this kind should be composed of metal parts that are simple in design, not liable to be deformed by the action of heat and a slight deformation of which will not be detrimental to their proper operation. In addition, the dimensions of the apparatus should be small so that no large-size pressure-resisting casings have to be used where the separation is to be effected from gases under pressure.

Moreover, the units composing the apparatus should be simple and it should be possible to connect them in series in order to enhance the cleaning effect or in parallel in order to increase the output.

The unit of the apparatus according to the invention comprises a double channel delimited by plane or substantially plane metal sheets, generally three of them composing an elemental section of the unit, arranged substantially parallel to and at very small distances from one another. The gas to be purified flows firstly through the channel comprised between one of the outer sheets and the central one, then in the reverse direction through the channel comprised between said central sheet and the other outer sheet. As the gas passes from the first channel into the second one its direction of flow is deflected through an angle of 180° over a bend of very small radius, whereby the removal of the dust is performed by the action of the centrifugal force upon the particles.

Of course, the passage leading from the first

channel into the second one should be so dimensioned in dependency on the character and size of the particles to be eliminated that a satisfactory operation of the apparatus is secured.

5 A first solution of this problem consists in providing a passage forming the bend continuous with the leading in channel, this passage being delimited by a wall that in a particular embodiment may be an extension of either or both of the outer walls, said wall being provided with one or several slits suitably located to facilitate the discharge of the particles to be removed.

A further solution consists in having the three parallel sheet metal walls with their edges substantially in a plane transverse to the planes of the sheets, the channels therebetween opening freely into a chamber in which the dust is collected.

A third solution consists in inwardly offsetting 20 from the transverse plane the edge of the inner or central wall with respect to the edges of the outer ones in an arrangement which otherwise remains the same as the second solution.

Units similar to the ones just described may be 25 grouped in series, also by pairs in order to lessen head losses between two successive units.

In another embodiment the units may also be arranged radially about a common axis of rotation within a slotted cylindrical coaxial barrel 30 connecting them with one another, the median plane of each unit going through said axis of rotation. The rotor comprising the barrel and the units may be rotated at high speed, the design of the inner channels being such that the gases 35 to be purified are taken into the apparatus through the one end plate of the barrel and out of it through the opposite end plate while a dust collector surrounds the rotor.

Of course, where the gas to be purified is under 40 pressure, the units should be arranged within a pressure-resisting casing. In this case special steps should be taken to avoid the condition that removal of the accumulated dust is attended with a loss of the gas under pressure. Such 45 removal may be effected, according to the invention, by spraying water into the apparatus in such a manner that a sludge is formed therewith that is discharged to the outside of the pressure resisting casing through a pipe the diameter and length of which are so chosen that continuous removal is secured without any risk of clogging and at reasonably low costs.

Several embodiments of the present invention are illustrated by way of example in the appended drawing.

Figures 1, 2, 3 respectively show the three aforementioned solutions or types of dust-removing units.

Figure 4 is a diagrammatical longitudinal view, and Figure 5 a cross-sectional view taken on line V—V in Fig. 4, which show a dust-removing apparatus comprising a single group formed of a plurality of units.

Figure 6 illustrates a dust-removing apparatus composed of two groups of units in series in opposed relation.

Figure 7 shows a dust-removing apparatus comprising three groups of units in series in a different arrangement.

Figures 8 and 9 diagrammatically show a rotary dust-removing apparatus in longitudinal and cross-sectional views respectively.

Figure 10 diagrammatically shows a dust-removing apparatus for removing dust from gases under pressure, together with its hydraulic dust-discharging system.

In the dust-removing unit shown in Fig. 1, the dust-laden gas is led in through channel 1 and out through channel 2 as a thin layer. At 3 a bend is formed in which the particles are urged outwardly by the centrifugal force and tend to escape through a slit 4 into a chamber outside the unit. The channels and the bend are defined by walls made of thin sheet metal. Experience has shown that if suitably dimensioned and operated with suitable gas flow speeds such a unit possesses a high separating capacity which, of course, is dependent on the character and size of the dust particles. The radius of curvature of the passage forming the bend is of the order of a few millimetres or of one centimetre.

According to Fig. 2 the wall defining the bend is dispensed with, and so it is in Fig. 3 in which the side walls extend beyond the middle one.

These elemental units forming U-shaped channels are juxtaposed in any desired number to deal with any desired gas flow.

Figure 4 shows a dust-removing apparatus composed of similar units contained in a casing or chest and so arranged that the gas flows in from conduit 5 and out to conduit 6 and is deflected through the unit as shown by the arrow. For that purpose a barrier partition or end wall 9 is provided which closes the remote ends of the channels through which the gas to be purified is led in from conduit 5 and prevents it from flowing out directly through conduit 6, said partition 9 being apertured to provide a free exit at this end of the channels through which the purified gas after sharp reversal of its flow is led out to conduit 6. The entering gas is prevented from entering these reverse flow channels by barrier walls 9' which in the embodiment of Figs. 4, 5, 6 and 7 are inclined to the direction of the entering gas, the walls between the channels being of generally triangular shape.

The barrier walls 9, 9' provide means cooperating with the walls of the units and with the casing to confine the gas to flow from the inlet opening in succession through the channels with reversal of the flow about the central walls or partitions of the units. The casing, moreover, provides means cooperating with the walls of the units to insure such gas flow and to effect discharge of the materials suspended in the gas under the centrifugal force developed by such reversal. The dust particles settle in a hopper 7 which, if desired, may contain baffles by which the dust already deposited is retained and pre-

vented from being whirled up back into the gas flow. A hand- or power-actuated rake 8 serves to clean the narrower portions of the channels.

Experience has shown that by providing a fan adapted to suck a small fraction of the gas from the hopper the efficiency of the apparatus is increased. This fan 40 forces the more or less purified gas thus tapped from the hopper again into the intake 5 of the apparatus.

The dust remover shown in Fig. 6 is composed of two units similar to the one shown in Fig. 4, with the peculiarity that they are arranged symmetrically and that their side walls 9 are contiguous. The barrier partitions 9 retain the gases from flowing directly from the intake 5 to the outlet 6. On the other hand they allow them to flow from hopper 10 into hopper 11.

As shown in Fig. 7, the dust remover comprises three units. It will be appreciated that the dust-removing effect is improved according as the gas passes through a larger number of units, which is confirmed by experience. The units may have unequal sections so that the flows therethrough are unequal. They may be arranged one after the other in a straight line or otherwise, e. g. in a helix.

Figs. 8 and 9 illustrate a dust remover which likewise comprises units providing channels 12, 13 defined by partitions 31, 32, 33 arranged in a rotor driven at high speed. The units are formed so that channels 12, 13 are radial. Four of these units are shown in the drawing, yet a less number or a considerably larger number of them may be used if desired. The gas is taken in at the inlet 14 and out at the outlet 15 and its paths of flow are indicated by the arrows. In the outer portions 16 of the channels flow reversing passages are formed in which the centrifugal effect of the rotation adds to the removing action of the unit which is secured by sharp reversal of direction about the edge of partition 31. The particles settle in the annular chamber provided by casing 35 and fall into hopper 17 connected to the bottom of this casing. The casing 35 and the walls of the rotor which provide the channels 12, 13 cooperate to confine the gas to flow in succession through these channels and to be reversed in passing from one to the other so that the combined effects of reversal and of centrifugal force due to the rotation insure the separation of the particles from the gas.

The rotor is driven by means of the shaft 18 that carries a pulley 19 and is mounted in bearings 20. Stuffing boxes 21, 22 or similar devices are provided to prevent leakage between the separation chamber and the gas inlet and outlet and at the point of passage of the shaft through the inlet conduit 14. The rotor may be keyed on the same shaft as the fan or blower (not shown) which produces the circulation of the gas. If desired a plurality of rotors may be arranged in series upon the shaft 18 in the direction of the gas flow in order to improve the separating effect or a plurality of rotors may be arranged in parallel with respect to the gas flow in order to increase the output. Rakes may be provided to clean the narrower portions of the channels. The arrangement may be such that the gas flows through the rotor either in a generally ascending or a descending or in a horizontal direction.

If the gas to be purified is under pressure, the apparatus is housed in a pressure resisting vessel, which is easily conceivable with the rotary arrangement shown in Fig. 8 if the inlet conduit 14, the casing 35, the hopper 17 and the out-

let conduit therefrom are constructed to be pressure resisting. Fig. 10 illustrates a dust remover composed of stationary units similar to those of Figs. 4, 5 and 6 enclosed in a cylindrical pressure-resisting casing or pressure vessel. This embodiment is composed by way of example of four units 23 arranged symmetrically by pairs. The dust laden gas under pressure enters through inlet 5 and after passing in series through the units 23 is discharged under pressure at outlet 6. The dust settles in the hoppers 24. Partitions 25 separate the hoppers and units in the same manner as do partitions 9 in Fig. 6.

Such a dust remover may be constructed to operate under considerable pressure, i. e. 100 kgs./sq. cm. or more, and may confine gases at a very high temperature. It may be arranged within a gas- or water-jacketed pressure vessel cooled by a suitable gas or by water circulated through the jacket.

If desired the action of such dust removers, whether they be stationary or rotary, may be improved by ionization of the dust particles in the conventional manner.

The dust may be discharged from the hoppers of the pressure vessel of Fig. 10 either through a conventional lock chamber or with the aid of the device about to be described.

In Fig. 10, the dust falls from each hopper 24 through pipes 26 into which respectively water is forced by a pump 27 through pipe 37 and branches 38, 39. The dust mixes with the water and the resulting quite fluid sludge is collected in a tank 28 which is subjected through pipes 26 to the pressure prevailing in the dust remover and is constructed to withstand this pressure. Owing to this pressure, the sludge may be continuously discharged to the atmosphere through a pipe 29. The sectional area of the pipe 29, however, is so chosen that the rate of flow therethrough is not so great as to cause a reduction in the pressure within the pressure vessel and in the tank 28 and on the other hand is sufficient for continuous discharge of the sludge as it is formed without clogging of the pipe. Without requiring an excessive length of the pipe 29 the sectional area of the pipe may be sufficiently restricted to limit the flow therethrough to maintain the pressure without developing velocities in the pipe 29 which would cause excessive wear. The pressure drop necessary for discharging the sludge from the tank under high pressure to the atmosphere is accomplished, however, by the restriction of the area for flow through the pipe 29 and the water thus discharged from the tank is replaced by the pump 29 which is capable of delivering this water against the pressure within the tank 29. Suitable control means controlling the delivery of the water to the tank may be used for keeping the water in the tank 28 substantially at a given level therein. Experience has shown that such a device for removal of the dust separated within a pressure vessel is quite suitable for the purposes of the invention.

The invention is applicable to all kinds of gases and dust particles. It is also applicable to the removal of liquid particles in suspension in gases or vapours.

The flow through the units may be horizontal, vertical or oblique in the different embodiments provided the hoppers are suitably arranged in relation to the passages between the channels of the units so as to collect the material separated from the gas in these passages due to reversal of the flow therein.

What we claim is:

1. Apparatus for separating from a gas material suspended therein which comprises a casing providing a separating chamber and having a gas inlet opening at one side of said chamber and a gas outlet opening at the opposite side of said chamber, at least one particle removal unit supported in said chamber providing a pair of narrow generally parallel channels defined by a partition wall and two outer walls generally parallel thereto and spaced therefrom at opposite sides thereof, means conducting the gas with said material suspended therein through said inlet opening into said chamber for flow therethrough toward said outlet opening, said walls of said unit being disposed parallel to the direction of flow from said inlet opening toward said outlet opening, means cooperating with said walls of said unit and with said casing for confining said gas to flow from said inlet opening through the channel between said partition wall and one of said outer walls of said unit and then about an edge of said partition wall to flow reversely through the other channel between said partition wall and the other outer wall of said unit, means cooperating with said walls of said unit and with said casing for withdrawing through said outlet opening the gas from said other channel of said unit, means cooperating with said partition wall and said outer walls of said unit for effecting discharge of the material suspended therein from said gas under the centrifugal force of reversal of its flow in passing from the first channel to said other channel, and means for collecting said material discharged and separated from said gas for removal from said casing.

2. Apparatus for separating from a gas material suspended therein which comprises a casing providing a separating chamber and having a gas inlet opening at one side of said chamber and a gas outlet opening at the opposite side of said chamber, at least one particle removal unit supported in said chamber providing a pair of narrow generally parallel channels defined by a partition wall and two outer walls generally parallel thereto and spaced therefrom at opposite sides thereof, means conducting the gas with said material suspended therein through said inlet opening into said chamber for flow therethrough toward said outlet therefrom, said walls of said unit being disposed parallel to the direction of flow from said inlet opening toward said outlet opening, a barrier wall spanning across at least one of said channels and cooperating with said partition and outer walls of said unit and with said casing to confine the gas from said inlet opening to flow through one of said channels and to reverse its flow about an edge of said partition wall and to flow reversely through the other channel toward said outlet from said chamber, said barrier wall preventing flow of the gas between said channels about said partition wall diverging from said flow of said gas along said first channel and then reversely along said other channel, means cooperating with said partition wall and said outer walls of said unit for effecting discharge of the material suspended therein from said gas as reversal of its flow is effected in passing from said first channel to said other channel, and means for collecting said discharged initially suspended material for removal from said casing.

3. Apparatus for separating from a gas material suspended therein which comprises a cas-

ing providing a separating chamber and having a gas inlet opening at one side of said chamber and a gas outlet opening at the opposite side of said chamber, at least one particle removal unit supported in said chamber providing a pair of narrow generally parallel channels defined by a partition wall and two outer walls generally parallel thereto and spaced therefrom at opposite sides thereof, means conducting the gas with said material suspended therein through said inlet opening into said chamber for flow therethrough toward said outlet therefrom, said walls of said unit being disposed parallel to the direction of flow from said inlet opening toward said outlet opening, a barrier wall extending transversely of said partition wall and cooperating therewith and with one of said outer walls of said unit and with said casing to confine said gas from said inlet opening to flow directly into one of said channels to flow therealong and to prevent flow of said gas directly into said other channel, a barrier wall extending transversely of said partition wall and cooperating therewith and with the other outer wall of said unit to close the end of said first channel disposed toward said casing outlet, said walls and said casing cooperating to confine the gas to flow along said first channel and to be reversed about an edge of said partition wall and then to flow along said other channel toward said outlet while being prevented from flowing from said other channel back into said first channel, and means cooperating with said partition wall and said outer walls and said casing adjacent said edge of said partition wall for collecting material initially suspended in said gas and discharged therefrom as reversal of its flow is effected about said edge of said partition wall.

4. Apparatus for separating from a gas material suspended therein which comprises a casing providing a separating chamber and having a gas inlet opening at one side of said chamber and a gas outlet opening at the opposite side of said chamber, a plurality of generally parallel partition walls supported in said chamber in spaced relation to each other, means for conducting the gas with said material suspended therein through said inlet opening into said chamber for flow therethrough toward said outlet opening, said partition walls being disposed parallel to the direction of flow from said inlet opening toward said outlet opening, barrier walls disposed with respect to said partition walls toward said inlet and extending transversely of said partition walls across the alternate channels therebetween to prevent entrance of said gas into said barriered channels, said partition walls cooperating with said casing and said barrier walls to confine said gas to flow into the other unbarriered channels between said partition walls and to flow in parallel paths therealong, means for conveying said gas from said outlet opening of said casing, barrier walls extending transversely of said partition walls across said channels into which said gas flows at the ends thereof disposed with respect to the gas flow toward said conveying means while leaving open at the ends thereof disposed toward said conveying means said channels barriered adjacent said gas inlet, said casing cooperating with said partition walls and said barrier walls to provide passages communicating between adjacent channels to produce flow of said gas along the channels into which said gas flows from said inlet and thereafter flow of said gas along said

alternate channels to be discharged therefrom to said conveying means, said passages being formed adjacent respective edges of the partition walls separating the channels in which said gas flows in opposite directions for effecting sharp reversal of said flow about said edges and separation by centrifugal force in said passages from said gas of said material suspended therein, and means cooperating with said casing and said partition walls and said barrier walls for collecting the material initially suspended in said gas and separated therefrom in said passages.

5. Apparatus for separating from a gas material suspended therein as defined in claim 4 in which said partition walls are arranged in parallel planes and are of generally right angle triangular shape in said planes with the hypotenuse edges thereof extending at an inclination to the flow of the gas entering said casing and with the other edges of said triangles respectively parallel to and at right angles to said entering flow, said transverse barrier walls which are disposed toward one of said openings of said casing extending along said hypotenuse edges of said partition walls, said barrier walls disposed toward the other opening of said casing extending along said edges of said partition walls which are at right angles to said entering flow of said gas, said casing cooperating with said partition walls and said barrier walls to form said passages communicating between adjacent channels adjacent the respective edges of said partition walls which extend parallel to the entering flow of said gas into said chamber, whereby said gases entering said chamber are confined to turn and to flow through alternate channels generally at right angles to said entering flow and then to turn sharply about said edges which extend parallel to said entering flow and thereafter to flow reversely through said other channels and again to turn generally at right angles to the flow in said other channels toward said outlet opening and said means for conveying said gas from said casing.

6. Apparatus for separating from a gas material suspended therein as defined in claim 1 in which said casing is constructed as a pressure vessel capable of confining gas at substantial pressure therein, said unit being supported within said pressure vessel, said means for collecting said discharged and separated material for removal from said casing being connected to means adapted to effect said removal while cooperating with said casing to confine said gas under pressure within said pressure vessel.

65 7. Apparatus for separating from a gas material suspended therein as defined in claim 6, said means for effecting removal of said discharged separated material comprising a tank connected to said collecting means and to said pressure vessel to receive the discharged separated material while subjected to said pressure, means for delivering liquid under pressure to said tank for mixture therein with said separated material, and means for discharging said mixture of said liquid and said separated material continuously from said tank while maintaining said pressure of said gas within said tank and said pressure vessel.

70 8. Apparatus for separating from a gas material suspended therein as defined in claim 2 which comprises a plurality of said units arranged within said casing for flow of said gas in series therethrough, said partition and outer walls in each unit having generally parallel edges

inclined with respect to the direction of gas flow through said unit, said barrier walls being inclined along said edges, said edges in adjacent units being inclined in the same direction with respect to the direction of the gas flow through said casing.

9. Apparatus for separating from a gas material suspended therein as defined in claim 2 which comprises a plurality of said units arranged within said casing for flow of said gas in series therethrough, said partition and outer walls in each unit having generally parallel edges inclined with respect to the direction of gas flow through said unit, said barrier walls being inclined along said edges, said edges in adjacent units being inclined in opposite directions with respect to the direction of the gas flow through said casing.

10. Apparatus for separating from a gas material suspended therein which comprises a casing providing a separating chamber, a member rotatable within said chamber constructed to provide a passage for flow of gas therethrough from an inlet opening thereof disposed generally centrally with respect to the axis of rotation to an outlet opening thereof disposed generally centrally with respect to said axis of rotation, a particle removal unit carried by said rotatable member and cooperating therewith to confine said gas to flow therethrough from said inlet to said outlet opening of said member, said particle removal unit being constructed with a generally radially extending partition wall between two outer walls generally parallel to said partition wall and disposed at opposite sides thereof in spaced relation thereto to provide a pair of narrow channels extending generally radially with respect to said axis of rotation, said walls being formed in relation to each other and to said rotatable member to provide a flow reversing passage disposed radially outwardly of and providing communication between said two channels and communicating outwardly with said chamber, said partition and outer walls cooperating with said rotatable member and with said casing to confine said gas to flow from said inlet opening into one of said channels and to flow radially outwardly in said channel and to flow through said outwardly disposed flow reversing passage and radially inwardly in said other channel to said outlet opening of said rotatable member, means for rotating said rotatable member to produce the action of centrifugal force on the material suspended in said gas to cooperate with the centrifugal force produced by reversal of said gas flow in said outwardly disposed flow reversing passage for effecting separation of said suspended material from said gas and discharge thereof outwardly into said chamber, and means cooperating with said

45
50
55
60

chamber for collecting and removing said material separated from said gas.

11. Apparatus for separating from a gas material suspended therein as defined in claim 10 which comprises a plurality of said particle removal units carried by said rotatable member and disposed symmetrically about said axis of rotation.

12. Apparatus for separating from a gas material suspended therein as defined in claim 10 in which said outlet opening of said member is displaced along the axis of rotation from said inlet opening, whereby the gas flows from said inlet opening generally along said axis of rotation to said outlet opening.

13. Apparatus for separating from a gas material suspended therein as defined in claim 10 in which said partition wall of said unit is connected by a barrier wall to a wall of said rotatable member to separate the gas flowing from said inlet opening into said channel to flow radially outwardly therein from the gas flowing radially inwardly in said other channel to said outlet opening.

14. Apparatus for separating from a gas material suspended therein as defined in claim 1 in which said particle removal unit is provided with a member supported for reciprocating movement thereof in the direction parallel to said partition and said walls of said unit and adjacent said edge of said partition wall about which said gas flows into said other channel, said member being provided with fingers respectively extending into said channels for cleaning said channels of particles deposited on said partition wall and said two outer walls of said unit.

15. Apparatus for separating from a gas material suspended therein as defined in claim 1 which comprises means for withdrawing from said chamber a portion of the gas adjacent said edge of said partition wall about which the flow of said gas is reversed and for delivering said withdrawn portion to the casing adjacent the inlet opening into said chamber.
